AXEL HASSELGREN AND DENNIS B. NEWMAN, OF ANSONIA, CONNECTICUT.

PENCIL-CLIP.

1,356,143.

Specification of Letters Patent.

Patented Oct. 19, 1920.

Application filed December 11, 1919. Serial No. 344,098.

To all whom it may concern:

Be it known that we, AXEL HASSELGREN and DENNIS B. NEWMAN, both citizens of the United States, residing at Ansonia, in the county of New Haven and State of Connecticut, have invented a certain new and useful Improvement in Pencil-Clips, of which the following is a specification.

This invention relates to pencil clips, but more particularly to that class of the same which are designed for holding pencils and the like behind the ear, although by a particular adjustment of parts it may be adapted for holding pencils and the like in the pocket of a coat or other garment.

The object of the invention is to provide an economical and durable device of this character which can be slipped on to the pencil in either direction and when in position on the pencil can be opened by means of a spring finger to admit that portion of the ear in front of the pencil.

In the drawings:

Figure 1 is a side view of the clip showing the spring finger in its depressed or open position;

Fig. 2, a top view of the same;

Fig. 3, a central, longitudinal, sectional view of the clip before it is slipped on to the pencil;

Fig. 4, a cross sectional view taken on line $\alpha-\alpha$ in Fig. 3;

Fig. 5, a view of the blank from which the ferrule portion of the clip is made, and

Fig. 6, a view of the blank bent up ready to be assembled.

The device primarily consists of two parts, that is the attaching ferrule 2 and the finger 3. The attaching ferrule 2 is formed of a blank like that shown in Fig. 5 in which the sides and ends are cut to desired shape so that when the flat blank is bent up into circular form it will have the curved ends and cut away side portions shown in Figs. 1, 2 and 3. In laying out the blank shown in Fig. 5 the side ears 4, 4 of the ferrule are formed by slitting the blank for a portion of its length adjacent to one end thereof as shown by the slot 5, and also making a slit at right angles to the slot 5 by giving opposite curvatures to the edges of the metal 6, 6. Adjacent to these curved edges and concentric therewith are formed

55 the pintle holes 7, 7. When the blank is

thus slit and bent to the circular configuration the ears 4, 4 are parallel with each other and stand straight upwardly from the sides of the ferrule, as shown in Fig. 6. Aside from the manner of forming the side ears 4, 4 on the ferrule, this latter may be made of any suitable construction to slip over the ordinary pencil or like article on which it is desired to use the clip. The slitting of the blank, however, in two directions and the bending up of the slotted portions to form side ears is one of the principal features of our invention. The finger piece 3 is provided at its rearward extremity with a flared plate 8 which is joined to the finger 3 at its forward end. Depending from each side of the forward end of the flared plate 8 are the side ears 10, 10 which are just wide enough to fit snugly between the side ears 4, 4 on the ferrule 2. The side ears 10, 10 are provided with apertures, one of which is shown at 11 in Fig. 3, which apertures are in alinement with the apertures 7, 7 in the side ears 4, 4 when the parts are brought into their assembled relation. The two sets of side ears are hinged together by a pintle 12 headed on each extremity to prevent its removal and on which swings the finger 3 against the action of the coiled spring 13, one extremity 14 of which presses against the top of the ferrule and the other extremity 15 presses against the under side of the flat plate 8. This coiled spring normally holds the extremity or ball 16 of the finger piece close against the side of the pencil but when pressure is brought to bear on the flaring plate 8 against the action of the coiled spring the finger 3 is of such a shape as to bring the ball thereof a slight distance from the pencil and the finger properly spaced from the adjacent side of the pencil as shown in Fig. 1, or in other words, the curve in the finger will clear or pass around the top edge of the ear forming a pocket for the same.

When it is desired to clip the pencil behind the ear the end of the pencil toward which the finger 3 points is passed behind the ear and the flaring plate 8 depressed by the thumb leaving a suitable space between the finger 3 and the adjacent side of the pencil for the passage of the adjacent portion of the ear. When the thumb is released from the flaring plate 8 the coiled

spring 13 acts to press the ball 16 against the front of the ear and thereby holds the same clipped to the pencil.

The coiled spring 13 is shown with its short extremity 14 pressing against the pocket 17 formed in the edge of the base or ferrule 2. By removing the clip, however, from the pencil as shown in Fig. 3, the tension on the spring becomes loose or is removed so that the spring may be moved laterally as shown in dotted lines in Fig. 4, wherein the short end 14 of the spring has been moved out of the pocket 17 down the curved edge toward the side ear 4. This results in loosening the tension or partly removing the tension from the spring 13 since its extremities 14 and 15 are held farther apart than when the clip is passed again over the pencil. In this manner the tension on the spring is made adjustable to accommodate it to different sizes of ears so that when it is used in connection with a person having a small ear the end 15 will be seated in the pocket 17 and the tension increased, whereas when used by a person having a large ear the tension can be decreased to permit the clasping of the ear with less force. This is one of the principal features of the invention.

It should be noticed that when the clip is in position on the ear due to the circular shape of the finger which clasps the edge of the ear it does not pinch the ear except

where the ball and pencil come together or clasp the ear, thereby leaving a pocket for the top edge of the ear between which and the barrel of the pencil the ear can be comfortably held.

While the above device represents the preferred form of the invention yet it is to be understood that the same may be modified provided that such modifications fairly come within the scope of the appended claim.

Having now described the invention what is claimed and desired to be protected by Letters Patent is:

A pencil-holder or the like comprising an attaching base or ferrule, a lever pivoted midway of its extremities upon said attaching base or ferrule, the said lever having that portion on one side of the pivotal connections flared to receive the pressure of the finger and that portion upon the opposite side of the pivotal connections designed to clip the ear, and a spiral spring for holding the lever closed on the ear, the said spiral spring being arranged to be moved around a portion of the circumference of the pencil on the edge of the ferrule when not under tension so that its maximum tension may be increased or decreased.

In testimony whereof, we have hereunto set our hands this 19 day of December, 1919.

AXEL HASSELGREN.
DENNIS B. NEWMAN.
